ABSTRACT

A variable resistor unit is provided which comprises a resistance element arranged in an annular configuration and a contact arm turnable on a shaft in sliding contact with the resistance element. The variable resistor unit with its shaft is supported by a support plate which is movable linearly as directed by guide means including a guide rod. A pulley is fixedly mounted on the shaft of the variable resistor unit, and a string wrapped around the pulley extends crosswise therefrom to have its ends tightly retained at both extremities of the stroke of the support plate. Hence, as the support plate is moved linearly by means of a knob affixed thereto, the pulley is turned by the string to cause the corresponding change in the angular position of the contact arm relative to the annular resistance element of the variable resistor unit.

FIG.11

**VARIABLE RESISTOR WITH LINEARLY
MOVABLE MEANS FOR CHANGING THE
RESISTANCE THEREOF**

BACKGROUND OF THE INVENTION

This invention relates to variable resistors, to volume controls, and to improved means for changing the resistance of a variable resistor of the rotary type by the linear motion of a knob or the like.

It is well known that the volume controls as heretofore used in various audio equipment of the like have usually been composed of a variable resistor of the rotary type including an annular resistance element and a contact arm mounted on a shaft. In order to change the resistance of such a rotary variable resistor, a knob affixed to the shaft has been manually revolved to cause the contact arm to turn in sliding contact with the resistance element.

More recently, however, there have been increasingly used the variable resistors comprising a linearly arranged resistance element and a contact arm which is movable linearly in sliding contact with the former to vary the resistance thereof. This latter type of volume controls seems to be currently preferred partly because of their appearance as actually incorporated in audio equipment and partly because of the ease with which they can be manipulated.

There is one serious disadvantage with the linear type of variable resistors, however, in that their resistance elements cannot possibly be enclosed in a dustproof housing. The accumulation of dust on the resistance elements results in the production of noise. Furthermore, the linearly arranged resistance elements tend to become detached, at least in part, from their insulating bases as the contact arms are moved repeatedly in sliding contact therewith. This can also seriously affect the operation of the variable resistors.

It should also be taken into consideration that for the fine adjustment of the resistance offered by the variable resistors of the linear type, the stroke of the knob and therefore of the effective size of their resistance elements must be considerably increased. However, the production of linear resistance elements of such increased size having unfluctuating resistance distribution is admittedly a very difficult task.

SUMMARY OF THE INVENTION

In view of the listed disadvantages and difficulties of the prior art, it is an object of this invention to provide a novel combination of a variable resistor of the rotary type and means for changing the resistance thereof by the linear motion of a knob or the like, such that the novel combination is particularly well suited for use as a volume control in various audio equipment or the like.

Another object of the invention is to provide apparatus of the character referred to, wherein the variable resistor in use can be completely enclosed in a dustproof housing so that its service life is greatly extended.

A further object of the invention is to provide apparatus of the character referred to, such that the fine adjustment of the resistance offered by the variable resistor can easily be made possible by suitably increasing the diameter of a pulley adapted to translate the linear motion of the knob into the rotary motion of a contact

arm in sliding contact with an annularly arranged resistance element of the variable resistor.

A further object of the invention is to provide apparatus of the character described, wherein a string is wrapped around the pulley in such a fashion that the linear motion of the knob is faithfully converted into its rotation.

A still further object of the invention is to provide apparatus of the character described, such that the knob can be moved linearly in either direction with minimum frictional resistance.

It is also an object of this invention to provide apparatus of the character referred to, which is positive in operation, simple and inexpensive in construction, and extremely easy to assemble.

With these objects in view and other objects herein-after made apparent, the present invention provides the combination including a variable resistor unit of the type having a resistance element arranged in a substantially annular configuration, a turnable contact arm, and a shaft supporting the contact arm. The variable resistor unit is supported by support means in such a manner that its shaft is turnable relative to the support means to cause the contact arm of the variable resistor unit to turn in sliding contact with the resistance element. The support means together with the variable resistor unit is linearly movable over a predetermined stroke as directed by guide means including a guide rod. A pulley is fixedly mounted on the shaft of the variable resistor unit for linear motion with the support means, and a string wrapped round the pulley extends crosswise therefrom to have its ends affixed at both extremities of the stroke of the support means. As the support means together with the variable resistor unit is moved linearly by means of a knob provided thereto, the pulley is turned by the string through an angle in proportion to the distance of travel of the support means thereby causing the corresponding change in the angular position of the contact arm relative to the resistance element through the shaft of the variable resistor unit. The guide means may include means adapted to minimize the frictional resistance offered to the linear motion of the support means.

The features which are believed to be novel and characteristic of this invention are set forth with particularity in the appended claims. The invention itself, however, both as to its construction and mode of operation, together with the further objects and advantages thereof, will become more apparent and understandable as the description proceeds, with reference taken to the accompanying drawings which illustrate, by way of example only, some preferred embodiments of the invention and in which like reference characters designate like parts throughout the several views.

BRIEF DESCRIPTION OF THE DRAWINGS

In the accompanying drawings:

FIG. 1 is a top view showing a knob movable on a slotted panel to change the resistance of a variable resistor according to this invention;

FIG. 2 is a front elevational view of a first preferred embodiment of the invention;

FIG. 3 is a view taken along the plane of line III-III in FIG. 2;

FIG. 4 is a side elevational view, partly in axial section, of a variable resistor unit incorporated in the embodiment of FIGS. 1 and 2;

FIG. 5 is an enlarged schematic view showing the internal construction of the variable resistor unit of FIG. 4;

FIG. 6 is a front elevational view of a second preferred embodiment of the invention;

FIG. 7 is a view taken along the plane of line VII-VII in FIG. 6.

FIG. 8 is a fragmentary back elevational view, partly in axial section, of a support plate and its guide rod in the embodiment of FIGS. 7 and 8;

FIG. 9 is a fragmentary side elevational view of the means shown in FIG. 8;

FIG. 10 is an enlarged perspective view of a slide cylinder employed to minimize the frictional resistance between the support plate and the guide rod best illustrated in FIG. 8 and 9; and

FIG. 11 is an enlarged, fragmentary, exploded perspective view showing a modified example of a string adapted to translate the linear motion of the knob into the rotary motion of a pulley in the embodiment of FIGS. 6 and 7.

DESCRIPTION OF THE PREFERRED EMBODIMENTS

A first preferred embodiment of this invention will now be described in detail with reference to FIGS. 1 to 5. Referring first to FIGS. 1 and 2, there is provided an elongate panel 10 having a slit 11 extending longitudinally thereof. A support plate 12 of substantially rectangular shape provided below the panel 10 has its tongue 12a rigidly coupled to a knob 13 through the slit 11. A pair of terminal members 13a and 13b are secured to the lower surface of the panel 10 at or adjacent both extremities of the slit 11 formed therein. Affixed at 14 to one of the surfaces of the support plate 12 is a variable resistor unit of the rotary type having a shaft 15 projecting outwardly therefrom to the other side of the support plate 12. The variable resistor unit 14 may include a dustproof housing enclosing various operative parts thereof as in the drawings.

As best shown in FIG. 3, a pulley 16 is screwed as at 17 to the shaft 15 of the variable resistor unit 14 on the said other side of the support plate 12. This pulley has a pair of parallel grooves 18a and 18b formed circumferentially thereof to accommodate a cord or string 19 which may be formed of wires, nylon fibers, or the like or which may be provided in the form of a belt of appropriately small width. The string 19 is wrapped a single turn around the pulley 16, crossing from one of the parallel grooves 18a and 18b to the other through an indentation 20 formed in the raised border herebetween. If desired, the string 19 may be affixed to the pulley 16 at the indentation 20 as by means of a screw 21, although this is not absolute necessity. Upon completely encircling the pulley 16 in this manner, the string 19 further extends crosswise substantially tangentially thereof to have its end tightly affixed to the terminal members 13a and 13b, respectively. In the illustrated embodiment of the invention the ends of the string 19 are inserted into bores 22a and 22b, respectively, of the members 13a and 13b and are unloosely retained by screws 23a and 23b, respectively.

In order to assure the linear motion of the support plate 12 and the knob 13, a guide rod 24 extends between the terminal members 13a and 13b through a

bore 25 formed in a member 26 secured to the support plate 12 as by means of screws 27.

As illustrated in detail in FIGS. 4 and 5, the shaft 15 of the variable resistor unit 14 rotatably supported by a bearing block 28 which is externally screw threaded to mesh with the corresponding internal threads of a nut 29 adapted to hold the variable resistor unit securely in position on the support plate 12. The variable resistor unit is of such construction that its shaft 15 is fixedly provided with a contact arm 30 which as the shaft 15 is revolved in a manner hereinafter set forth, turns in sliding contact with a resistance element 31 arranged in a substantially annular configuration on an electrically insulating base 32 and having terminals 33 and 34 connected to both extremities thereof. Thus, with the change in the angular position of the movable contact arm 30 relative to the resistance element 31, the electrical resistance between the terminal 33 and a terminal 35 electrically connected to the contact arm 30 and that between the terminal 35 and the other terminal 34 are varied as desired.

Proceeding now to the description of a mode of operation of the first preferred embodiment of the invention, constructed as hereinbefore described, the knob 13 may manually be moved in either direction along the slit 11 to cause the corresponding variation in the resistance offered by the variable resistor unit 14. Let it now be assumed that the knob 13 is moved to the left as viewed in FIGS. 1 and 2. Since the string 19 is affixed at one point to the pulley 16, or is at least tightly wrapped around the same, this pulley is caused to turn clockwise, as seen in FIG. 2, as it is pulled by that portion of the string 19 which extends from the terminal member 13b. Thus, with the leftward movement of the knob 13, the pulley 16 turns clockwise taking up more and more of the string portion extending between itself and the terminal member 13a while gradually releasing the string portion between itself and the other terminal member 13b.

The clockwise rotation of the pulley 16 is directly imparted to the shaft 15 of the variable resistor unit 14 on which the pulley is mounted, and the contact arm 30 also affixedly mounted of this shaft 15 is thus caused to turn in sliding contact with the resistance element 31 which is held stationary. In this manner the electrical resistance between the terminals 33 and 35 and that between the terminals 35 and 34 are each varied in proportion to the distance over which the knob 13 has been moved. It will be apparent that the contact arm 30 is caused to turn in the opposite direction relative to the resistance element 31 if the knob 13 is moved to the right as seen in FIGS. 1 and 2.

Another preferred embodiment of the invention is shown in FIGS. 6 to 11. With particular reference to FIGS. 6 and 7, this second embodiment also includes a panel 10 of substantially rectangular shape having a slit 11 extending longitudinally thereof, and a support plate 12 therebelow having its tongue 12a rigidly coupled to a knob 13 through the slot 11. A variable resistor unit 14 set forth in relation with the preceding embodiment of the invention is affixed in a similar manner to the support plate 12, that is, by a nut 29 meshing with an externally screw threaded bearing block 28 which rotatably supports the shaft 15 of the variable resistor unit. A pulley 16 is also screwed at 17 to the shaft 15. As previously mentioned, the variable resistor unit

14 may include a dustproof housing enclosing the various operative parts thereof.

The support plate 12 is integrally provided with a pair of arms 40a and 40b which are bent at right angles therewith and which have bores 41a and 41b, FIG. 8, therethrough. Snugly fitted in each of these bores is a slide cylinder 42 illustrated in greater detail in FIG. 10. Preferably formed of a fluorine resin with its extremely low coefficient of friction, the slide cylinder 42 includes a pair of flanges 43 and 44 of different diameters on both ends thereof defining a substantial groove 45 therebetween. The groove 45 has a width approximately equal to the thickness of the arm 40a or 40b, and the outside diameter of the slide cylinder 42 at this groove 45 is approximately equal to the diameter of the bore 41a or 41b. The slide cylinder 42 is hollowed longitudinally therethrough as indicated at 46 and is further slotted longitudinally at 47. A plurality of, three in this embodiment, ridges 48 are formed on its internal surface to minimize the friction with a guide rod 24 which is to be inserted into the hollow 46.

Due to the provision of the slot 47 the slide cylinder 42 is manually compressible to such as extent that at least its flange 44 of smaller diameter is permitted to pass through the bore 41a or 41b of the arm 40a or 40b. Once inserted into the bore in this manner, each slide cylinder 42 is securely retained in position by virtue of the flanges 43 and 44 as it regains its initial shape, as will be understood from FIGS. 8 and 9. The pair of slide cylinders 42 thus supporting the support plate 12, the variable resistor unit 14 and so forth are slideable on the guide rod 24 with minimum frictional resistance.

Referring back to FIGS. 6 and 7, the guide rod 24 has its both ends inserted into and through bores 49a and 49b formed in the terminal members 13a and 13b which in this embodiment of the invention are formed by downwardly bending both ends of the panel 10. The ends of the guide rod 24 projecting out of the bores 49a and 49b are retained by snap rings 50a and 50b, respectively. The guide rod 24 may be greased to assure smoother sliding of the support plate 12 and so forth.

Since the support plate 12 and the various means affixed thereto may turn to and fro when supported only by the guide rod 24, the panel 10 is substantially integrally provided with a downward extension 51 which is folded at its lower end to provide a guide plate 52 extending parallel to the guide rod 24, as may be best understood from FIG. 7 in particular. The guide plate 52 is sandwiched between the support plate 12 and a leaf spring 53, the latter being screwed at 54 to the former. In order to reduce the frictional resistance which may be caused by the guide plate 52, convexities 55 and 56 are formed correspondingly on the confronting surfaces of the support plate 12 and the leaf spring 53, such that the guide plate 52 makes substantial point contact therewith. This guide plate may also be greased to further reduce the frictional resistance.

As in the preceding embodiments of the invention the pulley 16 screwed at 17 to the shaft 15 of the variable resistor unit 14 is provided with a pair of parallel circumferential grooves 18a and 18b to receive the cord or string 19 explained previously in relation with the FIGS. 1 to 5 embodiment. The raised border 57 between these parallel grooves is indented at one point thereof as seen in FIG. 7, and the string 19 crosses the raised border 57 at this indentation from one of the

parallel grooves to the other. Although the string 19 may be affixed to the pulley 16 as in the first described embodiment of the invention, it can also be retained solely by the opposed edges 58a and 58b of the raised border 57 if the spacing between these edges is made sufficiently small.

After making a complete turn around the pulley 16, the string 19 further extends crosswise substantially tangentially thereof to have its end tightly affixed to the 10 terminal members 13a and 13b, respectively, in a manner hereinafter described by way of example. Both ends of the string 19 are first inserted into bores formed through member 59a and 59b of stepped cylindrical shape (shown in the more detail in FIG. 11) and are retained therein as by means of screws 60a and 60b, and these members are engaged by slots 61a and 61b (also shown in FIG. 11) formed in the terminal members 13a and 13b. It will be seen that the members 59a and 59b are removably but securely retained in the slots 61a and 61b by the steps formed on their circumferences.

The second preferred embodiment of this invention being constructed as hereinbefore set forth, the knob 13 may manually be moved linearly in either direction 25 along the slit 11 of the panel 10 to cause the corresponding change in the electrical resistance offered by the variable resistor unit 14 of the construction shown in FIG. 5. With the motion of the knob 13 the support plate 12 and the various means affixed thereto are also 30 caused to move in the same direction as guided by the guide rod 24 and the guide plate 52. The smooth sliding motion of the support plate 12 and so forth is ensured since the guide rod 24 is in contact only with the ridges 48 formed on the internal surfaces of the slide cylinders 42 and since the guide plate 52 is in contact only with the convexities 55 and 56 formed on the confronting surfaces of the support plate 12 and the leaf spring 53. Further details of operation of this embodiment of the invention will be apparent from the foregoing description of operation of the FIGS. 1 to 5 embodiment.

FIG. 11 illustrates a modification of the string 19 in the second embodiment of the invention, in which one or both ends of the string are connected to one end of a helical tension spring 62 adapted to impart suitable resiliency thereto. The other end of the spring 62 is inserted into the member 59a of stepped cylindrical shape as in the FIGS. 6 to 10 embodiment and is retained therein by the screw 60a. Also as in the preceding embodiment the members 59a and 59b are engaged by the slots 61a and 61b of the terminal members 13a and 13b. By thus imparting suitable resiliency to the string 19, both ends thereof can be affixed to the members 59a and 59b before these members are retained in position by the slots 61a and 61b, so that the installation of the string 19 is highly facilitated.

Although it is believed that the various objects of this invention, either explicitly stated or implicitly pointed out, are fully accomplished by the preferred embodiment herein disclosed, it is also to be understood that the invention itself is not to be restricted by the exact showing of the accompanying drawings and the description thereof. For instance, the string 19 may be affixed to the terminal member 13a and 13b or to the pulley 16 by means other than those disclosed herein. Thus, a latitude of modification, substitution and change is intended in the foregoing disclosure and in some instances some features of the invention will be

employed without the corresponding use of other features, while still remaining within the spirit and scope of the invention.

We claim:

1. In combination:

a variable resistor unit comprising a resistance element arranged in a substantially annular configuration, a contact arm turnable in sliding contact with said resistance element, and a shaft supporting said contact arm;

support means supporting said variable resistor unit in such a manner that said shaft is turnable relative to said support means to cause said contact arm of said variable resistor unit to turn in sliding contact with said resistance element;

guide means for directing the linear motion of said support means together with said variable resistor unit over a predetermined stroke;

a pulley fixedly mounted on said shaft of said variable resistor unit for linear motion with support means;

a string wrapped around said pulley and further extending crosswise substantially tangentially thereof to have its end affixed respectively to a pair of terminal members positioned adjacent both extremities of the stroke of said support means; and

a knob provided to said support means for manually moving the same linearly in either direction along said guide means whereby said pulley is turned by said string through an angle proportional to the distance said support means is moved, thereby causing corresponding change in the angular position of said contact arm relative to said resistance element through said shaft of said variable resistor unit.

2. The combination as defined in claim 1, wherein said support means include a support plate of substantially rectangular shape having a tongue to which is affixed said knob.

3. The combination as defined in claim 2, wherein said guide means comprise a guide rod slidably supporting said support plate at one end thereof, and a guide plate extending parallel to said guide rod and slidably sandwiched between said support plate and a leaf spring secured to said support plate at the other end thereof.

4. The combination as defined in claim 3, including a pair of convexities formed correspondingly on the confronting surfaces of said support plate and said leaf

spring to reduce the frictional resistance which might be caused by said guide plate slidably sandwiched therebetween.

5. The combination as defined in claim 3, wherein

5 said guide rod slidably supports said support plate through a pair of slide cylinders affixed to the latter, each of said slide cylinders being hollowed to receive said guide rod and having a plurality of ridges formed longitudinally on its internal surface to reduce the frictional resistance which might be caused by said guide rod.

10 6. The combination as defined in claim 5, wherein each of said slide cylinders has a pair of flanges of different diameters on both ends thereof and is formed of a resilient material, each of said slide cylinders being further slotted longitudinally so as to be manually compressible to such an extent that one of said flanges having a small diameter is permitted to pass through a bore formed in said support plate for installation in place.

15 7. The combination as defined in claim 5, wherein said slide cylinders are each formed of a fluorine resin having an extremely low coefficient of friction.

20 8. The combination as defined in claim 1, wherein said guide means include a guide rod slidably supporting said support means.

25 9. The combination as defined in claim 1, wherein said pulley has a pair of parallel grooves formed circumferentially thereof to receive said string, said string being wrapped a single turn around said pulley and crossing from one of said parallel grooves to the other through an indentation formed in a raised border therebetween.

30 10. The combination as defined in claim 9, wherein said string is screwed to said pulley at said indentation formed in the raised border between said parallel grooves.

35 11. The combination as defined in claim 1, wherein both ends of said string are securely retained by a pair of stepped cylindrical members, respectively, said stepped cylindrical members being each removably engaged by a slot formed in each of said terminal members.

40 12. The combination as defined in claim 11, including a helical compression spring extending between at least one of said stepped cylindrical members and the corresponding end of said string to facilitate its installation in place.
